MAGNETRON AMPLIFIERS

Edward C. Dench, Needham, Mass., assignor to Raytheon Company, a corporation of Delaware

Original application Nov. 8, 1951, Ser. No. 255,499, now Patent No. 2,809,328, dated Oct. 8, 1957. Divided and this application Apr. 30, 1957, Ser. No. 658,913

11 Claims. (Cl. 315—39.3)

This is a division of my application, Serial No. 255,499, filed November 8, 1951, now Patent No. 2,809,328.

This invention relates to electron discharge devices and more particularly to discharge devices of the magnetron amplifier type.

In copending application, Serial No. 81,804, filed March 16, 1949, by William C. Brown, now Patent No. 2,673,306, dated March 23, 1954, there is disclosed a magnetron amplifier wherein the anode of a cavity type of magnetron structure is constructed as a non-reentrant signal wave transmission network having input and output means connected, respectively, to the ends thereof. It has been found that the operation of devices of this type is quite critical since, if the gain is too high for a given set of impedance-matching conditions at the input and output of the device, oscillations may occur.

This invention discloses means whereby the gain and other operating conditions of the device may be adjusted. Briefly, this is accomplished by placing auxiliary electrodes outside the paths of electrons which pass adjacent the signal wave transmission network, portions of said electrodes being positioned adjacent the cathode of the device, and portions of the electrodes extending toward the anode structure of the device. By insulating these electrodes with respect to the anode and the cathode, a biasing potential may be applied thereto, and the gain, as well as other operating conditions of the device, may be adjusted by adjusting said biasing potential.

There is disclosed herein a first embodiment of this invention, wherein the anode structure surrounds a cylindrical cathode structure spaced therefrom such that the cathode structure emits electrons along substantially the entire length of the anode structure from the input to the output thereof. The auxiliary electrodes are in the form of discs positioned at the ends of the cathode structure, insulated therefrom and extending radially outward toward the anode structure. These auxiliary electrode discs take the place of the conventional end shields commonly used in magnetron structures to prevent movement of the electrons in a direction axial to the cylindrical cathode.

Other and further objects and advantages of this invention will be apparent as the description thereof progresses, reference being had to the accompanying drawings wherein:

Fig. 1 illustrates a longitudinal cross-sectional view of a first embodiment of this invention taken along line 1—1 of Fig. 2; and

Fig. 2 illustrates a partially broken-away transverse cross-sectional view of the device shown in Fig. 1.

Referring now to Figs. 1 and 2, there is shown an anode structure 10 comprising an anode cylinder 11. Extending radially inwardly from the inner surface of anode cylinder 11 is a plurality of anode members 12 comprising substantially rectangular planar members which lie parallel to the axis of cylinder 11. Members 12 are alternately connected at points near their inner ends on the upper and lower edges thereof by conductive straps 13, in a well-known manner, such that the straps 13, the

2

anode members 12 and the spaces defined therebetween constitute a signal wave transmission network having a high-frequency pass filter characteristic. At one point in the anode structure, the members 12 and the conductive strapping 13 have been eliminated such that the transmission network is of a non-reentrant type. A signal input coupling structure 14 is connected to one end of the signal wave transmission network by connecting one of the conductive straps 13 to the inner conductor 15 of a coaxial line having an outer conductor 16. The coaxial line comprising conductors 15 and 16 extends outwardly through an aperture in anode cylinder 11 with outer conductor 16 being sealed to said aperture. Outer conductor 16 is sealed to inner conductor 15 through a ceramic seal 17 which insulatedly supports inner conductor 15 with respect to outer conductor 16. The other end of the transmission line is connected to an output coupling device 18 comprising an inner conductor 19, an outer conductor 20 and a ceramic seal 21 similar, respectively, to members 15, 16 and 17 of input coupling device 14.

Extending inwardly from anode cylinder 11, in the space between the ends of the signal wave transmission network, is a conductive member 22. Member 22 extends inwardly from anode cylinder 11 for substantially the same distance as anode members 12, and is appropriately dimensioned to serve as a radio frequency choke, thereby preventing coupling of signal waves appearing at the output device directly across to the input device.

30 Positioned in the space defined by the inner ends of the anode members 12 is a cathode structure 23 comprising a cathode cylinder 24 whose outer surface is covered with electron-emissive material. The upper and lower ends of cathode cylinder 24 are covered by upper and 35 lower end plates 25 and 26, respectively. Rigidly attached to lower end plate 26 is a cathode support cylinder 27 which extends downwardly through an aperture in a lower end cover 28 which is hermetically sealed to the lower end of anode cylinder 11. Support cylinder 27 is 40 rigidly attached to a cup member 29, which, in turn, is sealed to a ceramic seal 30 surrounding anode support cylinder 27. Seal 30 is, in turn, attached to a cylindrical conductive member 31 surrounding support member 27 spaced therefrom, and sealed into a recess surrounding the aperture in cover plate 28 through which support member 27 passes. Positioned inside support member 27, which is hollow, is a conductive rod 32 which is 45 spaced from support member 27, one end of which extends into cathode cylinder 24 where it is connected to one end of a heater coil 33, the other end of heater coil 33 being connected to the cathode cylinder 24. Conductor 32 extends outwardly through the lower end of support member 27 and is insulatedly sealed thereto by means of a ceramic seal 34 in a well-known manner. By 50 application of a potential between a connector 35 attached to conductor 32 after it passes seal 34 and support cylinder 27 which is connected through lower end plate 26 to the cathode cylinder 24, a current may be caused to flow through the heater coil 33, thereby heating the cathode cylinder 24 to electron-emitting temperature.

55 Positioned above and below the cathode structure 23 are conductive discs 36 and 37, respectively, said discs extending outwardly to a point near the inner ends of anode members 12. Discs 36 and 37 are spaced from the cathode 23 and are rigidly attached together through 60 conductive rods 38, which extends through apertures in end plates 25 and 26, respectively, spaced therefrom. Lower disc 37 has an aperture therein to allow the passage of support cylinder 27 therethrough without contact therewith. The auxiliary electrode structure comprising discs 36 and 37 is rigidly supported with respect to the anode structure 10 and the cathode structure 23

by means of rods 39 rigidly attached to lower disc 37 and passing through apertures in lower cover plate 28, rigidly sealed thereto by means of ceramic buttons 40 positioned in the apertures in cover plate 28, surrounding and sealed to rods 39. By application of a suitable potential to the lead-in support rods 39, the auxiliary electrode comprising discs 36 and 37 may be maintained at any desired potential with respect to the cathode structure 23 or the anode structure 10.

While it is preferable that the auxiliary electrode structure be biased somewhat negative with respect to the cathode structure 23, it is to be clearly understood that this invention is not limited thereto since, if a certain amount of electron collection by the auxiliary electrode structure may be tolerated, an improvement in gain may be possible by biasing the auxiliary electrode structure positive with respect to the cathode structure 23.

The upper end of the anode cylinder 11 is closed by an upper cover plate 41, and a magnetic field is produced in the space between the inner ends of the anode members 12 and the cathode cylinder 24 by any desired means, such as a permanent magnet 41a or an electromagnet.

This completes the description of the embodiment of the invention described herein. However, many modifications thereof will be apparent to persons skilled in the art. For example, the device shown in Figs. 1 and 2 may be a linear device instead of a circular one. Furthermore, if desired, a blocking member could be attached to the cathode structure in the device of Figs. 1 and 2 at a point adjacent the radio-frequency choke member 22 to prevent electrons from continuing around the cathode from the output of the device to the input. Accordingly, it is desired that this invention be not limited to the particular details of the embodiments illustrated herein, except as defined by the appended claims.

What is claimed is:

1. An electron discharge device comprising a slow wave energy propagating structure for transmitting electromagnetic wave energy to an output, a source of electrons spaced from said structure, means for directing electrons from said source along the region between said structure and said source at a velocity substantially equal to the velocity of propagation of said wave energy, and an output amplitude control electrode structure insulated from said energy propagating structure and said source and including an electrically-conductive member positioned adjacent and outside said region and outside said structure.

2. An electron discharge device comprising a slow wave energy propagating structure for transmitting electromagnetic wave energy to an output, a source of electrons spaced from said structure, means for directing electrons from said source along the region between said structure and said source at a velocity substantially equal to the velocity of propagation of said wave energy, and an amplitude control electrode structure insulated from said energy propagating structure and said source and including an electrically-conductive member positioned adjacent and outside said region, and means for supplying an electrical potential to said control electrode for controlling the amplitude of said wave energy to said output.

3. An electron discharge device comprising a slow wave energy propagating structure for transmitting electromagnetic wave energy to an output, a source of electrons spaced from said structure, means for directing electrons from said source along the region between said structure and said source at a velocity substantially equal to the velocity of propagation of said wave energy, and an amplitude control electrode assembly insulated from said energy propagating structure and said source and including two spaced electrically-conductive electrodes positioned adjacent and outside said region and disposed on opposite sides of said region, and means for supplying an electrical potential to said control electrode assembly

for controlling the amplitude of said wave energy to said output.

4. An electron discharge device comprising a slow wave energy propagating structure for transmitting electromagnetic wave energy to an output, a source of electrons spaced from said structure, means for directing electrons from said source along the region between said structure and said source at a velocity substantially equal to the velocity of propagation of said wave energy, said electrons making more than one traversal past a given point along said structure, and an amplitude control electrode structure insulated from said energy propagating structure and said source and including two spaced electrically-conductive members positioned adjacent and outside said region and disposed on opposite sides of said region and facing said region and means for supplying an electrical potential to said control electrode structure for controlling the amplitude of said wave energy to said output.

5. An electron discharge device comprising a slow wave energy propagating structure for transmitting electromagnetic wave energy to an output, a source of electrons spaced from said structure, means for directing electrons from said source along an interaction space between said source and said structure at a velocity substantially equal to the velocity of propagation of said wave energy, and an output amplitude control electrode structure insulated from said energy propagating structure and said source and including an electrically-conductive ring positioned adjacent and outside said interaction space, the material of said ring being juxtaposed with said space.

6. An electron discharge device comprising a slow wave energy propagating structure for transmitting electromagnetic wave energy to an output, a source of electrons spaced from said structure, means for directing electrons from said source along said structure at a velocity substantially equal to the velocity of propagation of said wave energy, and an amplitude control electrode including at least one electrically-conductive member positioned adjacent and outside said structure insulated from said energy propagating structure and said source and facing said structure and insulated therefrom, and means for supplying an electrical potential to said control electrode structure for controlling the amplitude of said wave energy to said output.

7. An electron discharge device comprising a slow wave energy propagating structure having first and second ends for transmitting electromagnetic wave energy to an output, a source of electrons spaced from said structure, means for directing electrons from said source along the region between said structure and said source at a velocity substantially equal to the velocity of propagation of said wave energy, said means for directing including means for producing a magnetic field transverse to said region, and an output amplitude control electrode structure supported electrically insulated from the remainder of the device and including an electrically-conductive member positioned adjacent and outside said region and facing said region.

8. An electron discharge device comprising a slow wave energy propagating structure for transmitting electromagnetic wave energy to an output, a source of electrons spaced from said structure, means for directing electrons from said source along said structure at a velocity substantially equal to the velocity of propagation of said wave energy, and an output amplitude control electrode assembly supported electrically insulated from the remainder of the device and including two spaced electrically-conductive members positioned adjacent and outside said structure, said members being disposed on opposite sides of said structure.

9. An electron discharge device comprising a slow wave energy propagating structure for transmitting electromagnetic wave energy to an output, a source of elec-

trons spaced from said structure, means for directing electrons from said source along said structure at a velocity substantially equal to the velocity of propagation of said wave energy, and an amplitude control electrode assembly supported electrically insulated from the remainder of the device and including two electrically-conductive members positioned adjacent and outside said structure and disposed on opposite sides of said structure, said members being electrically at the same potential, means for supplying an electrical potential to said members for controlling the amplitude of said wave energy to said output.

10. An electron discharge device comprising a slow wave energy propagating structure having first and second ends for transmitting electromagnetic wave energy to an output, a source of electrons spaced from said structure and constructed to emit electrons at several positions over a major portion of the region between said structure and said source at a velocity substantially equal to the velocity of propagation of said wave energy, means 15 for directing electrons from said source along said region, and an amplitude control electrode assembly supported electrically insulated from the remainder of the device and including two spaced electrically-conductive members positioned adjacent and outside said region and disposed on opposite sides of said region and facing said region, and means for supplying an electrical potential to control members for controlling the amplitude of said wave energy to said output.

11. An electron discharge device comprising a slow 20 25 Proc. of I.R.E. for May 1936, vol. 24, No. 5.

wave energy propagating structure for transmitting electromagnetic wave energy to an output, a source of electrons spaced from said structure, means for directing electrons from said source along a region between said source and said structure at a velocity substantially equal to the velocity of propagation of said wave energy, an amplitude control electrode structure supported electrically insulated from the remainder of the device and positioned adjacent and outside said region, said members being arranged coextensive with and facing said region, and means for supplying an electrical potential to said control electrode structure for controlling the amplitude of said wave energy to said output.
